UNITED STATES PATENT OFFICE.

WINFIELD S. DOUGLASS, OF GLEN JEAN, WEST VIRGINIA.

IDENTIFICATION-BELT.

1,025,520.

Specification of Letters Patent.

Patented May 7, 1912.

Application filed May 16, 1911. Serial No. 627,523.

To all whom it may concern.

Be it known that I, WINFIELD S. DOUGLASS, a citizen of the United States, residing at Glen Jean, in the county of Fayette and State of West Virginia, have invented certain new and useful Improvements in Identification-Belts; and I do hereby declare the following to be a full, clear, and exact description of the invention, such as will enable others skilled in the art to which it appertains to make and use the same:

This invention relates to identification belts and has for an object to provide a belt and identification means carried thereby, whereby persons who are victims of accidents may be easily identified.

Another object is to provide a belt to be worn by miners and other workmen, said belt adapted to have suspended therefrom a numbered tag, or other means of identification, to make it possible to identify the workman should he be a victim of an explosion or other accident, and, another object is to provide means to securely fasten the tag or other article of identification to the belt worn by a workman.

Other objects and advantages will be hereinafter set forth and pointed out in the specification and claim.

In the accompanying drawings which are made a part of this application, Figure 1 is a perspective view of the belt and the tag holding means secured thereto, with a numbered tag or disk carried by the supporting means, while, Fig. 2 is a vertical sectional view on the line 2--2 of Fig. 1.

Referring to the drawings in which similar reference numerals designate corresponding parts throughout the several views, 1 represents the belt, which may be of the ordinary or any preferred form, and has riveted or otherwise secured thereto the downwardly extending protector 2, composed of leather or other suitable material and having the tongue 3 near its center and upon its outer surface, the purpose of which will presently appear.

Extending around the belt 1 and between the latter and the protector 2, is the rectangular portion 4 of the spring snap, which has the downwardly extending portion 5, which passes beneath the tongue 3 and the protector 2 and is curved below said tongue, as shown at 6, until the end thereof extends in an upward direction to form the outer finger 7 of the spring clip check supporter.

Pressing against the inner face of the finger 7 is the opposite curved end 8 of the spring identification check holder, which is directed at an angle, as shown at 9, to the vertical portion 5, said portions 5 and 9 meeting at a point 10 immediately below the belt 1, said portions extending in opposite directions from this point to form the lower part of the rectangular portion 4 of the supporter. A numbered disk 11, or other means of identification having a suitable perforation, as shown at 12, is slipped over the end of the finger 7 and drawn downwardly between this finger and the curved end 8 of the inner finger, until it passes the latter finger and is suspended freely from the curved portion 6 of the support, normally resting parallel with the protector 2.

It will be seen that the identification means 11 cannot be casually disengaged from the spring clip, and as the latter is securely engaged around the belt 1, there is no possibility of the workman losing his means of identification. The rectangular portion 4 is preferably passed between the belt 1 and the protector 2 between the rivets or other securing means fastening these two parts together, thus limiting the movement of the supporter longitudinally of the belt. The tongue 3 serves to limit the lateral movement of the lower portion of the disk supporter and the protector 2 serves to protect the wearer of the belt, preventing the lower end of the spring clip of the identification means 11 from pressing against his person, as it would otherwise be liable to do, especially when the workman bends or leans forward.

As is well known, explosions and other accidents often occur in mines and similar places where large numbers of workmen are daily toiling and the victims of these accidents frequently are without means by which they may be identified. Persons employed in such places and wearing this identification belt could easily be identified by the number of the disk 11, or other identification means suspended from the spring clip herein employed, and as this device is of extremely simple construction, requiring no alteration whatever in the present form of belt used by such workmen, it could be manufactured and sold at a price within the reach of all requiring such devices.

It will also be seen that the wearer of this identification belt is protected from injury

by the same, and as the identification means is securely fastened to the belt, it will always be in position and when the belt is in place the identification means will also be in place upon the workman.

What I claim is:

In a device of the class described the combination with a belt having a protector secured thereto and depending therefrom of means for securing the protector to the belt at spaced points, a suspending snap having a rectangular portion to engage the belt and depending therefrom between the points at which the protector is secured to said belt, said protector having a tongue near its central portion, the suspending snap being en-

gaged under the tongue and thus held against swinging movement upon the belt, said suspending snap being adapted to receive an object thereover and suspend the same from the belt, the protector limiting the longitudinal movement of the snap upon the belt and preventing said snap from injuring the wearer of the device.

In testimony whereof I have signed my name to this specification in the presence of two subscribing witnesses.

WINFIELD S. DOUGLASS.
